US00D600710S

(12) **United States Design Patent**
LaManna et al.

(10) **Patent No.:** US D600,710 S
(45) **Date of Patent:** ** Sep. 22, 2009

(54) **ICON FOR A DISPLAY SCREEN**

(75) Inventors: **Michael H. LaManna**, Bothell, WA (US); **Gavin M. Gear**, Seattle, WA (US)

(73) Assignee: **Microsoft Corporation**, Redmond, WA (US)

(**) Term: **14 Years**

(21) Appl. No.: **29/328,815**

(22) Filed: **Dec. 2, 2008**

(51) **LOC (9) Cl.** 32-00

(52) **U.S. Cl.** D14/492

(58) **Field of Classification Search** D14/485-495;
D18/26, 31-33; D20/11-12, 23-25, 29-32,
D20/36-38; 715/700-867, 973-977

CLAIM

The ornamental design for an icon for a display screen, as shown and described.

DESCRIPTION

FIG. 1 is a front view of an icon for a display screen showing our new design; and,

FIG. 2 is an additional front view thereof, showing additional unclaimed subject matter.

The broken line showing of the rectangular boxes in FIG. 2 and the display screen forms no part of the claimed design.

1 Claim, 2 Drawing Sheets

FIG. 1

FIG. 2
